UNITED STATES PATENT OFFICE.

WILLIAM HENRY DANIELS, OF MILFORD, INDIANA.

DESIGN FOR A SHARPENER FOR MOWER OR REAPER KNIVES.

SPECIFICATION forming part of Design No. 26,942, dated April 20, 1897.

Application filed March 6, 1897. Serial No. 626,330. Term of patent 14 years.

To all whom it may concern:

Be it known that I, WILLIAM HENRY DANIELS, a citizen of the United States, residing at South Milford, in the county of La Grange and State of Indiana, have invented a new and original Design for Sharpeners for Mower or Reaper Knives, of which the following is a full, clear, and exact specification, reference being had to the accompanying drawings, forming a part hereof, in which—

Figure 1 is a perspective view of a sharpening implement, showing my design. Fig. 2 is an elevation looking at one edge of the implement. Fig. 3 is a vertical cross-sectional view on the plane indicated by the dotted line 3 3 of Fig. 2.

The leading feature of my design consists in the working surfaces of different angularity—that is to say, the two working surfaces of the implement consist of faces arranged at an angle to each other, and the angle of the faces of one surface is different from the angle of the other working surface.

A designates the body of the sharpener, and B B are the central or axially-arranged

handles at the ends of said body. In general the body is rectangular, viewed in plan, and said body has two working surfaces, (indicated at C D in Fig. 3.) The working surface C consists of two faces c c', which lie at an angle to each other and meet or intersect in a ridge c² in the plane of the axial line of the body. The other working surface D has two faces d d', which lie at an angle to each other and also meet in a ridge d² in the plane of the longitudinal axis of the body, but the faces d d' lie at a different angle to each other than the angle produced by faces c c' of the opposite surface C.

In each of the surfaces C D are longitudinal grooves E, and the grooved surfaces are covered with a coating (indicated at F) which fills said grooves.

What I claim is—

The design herein shown and described for a sharpener for mower and reaper knives.

WM. HENRY DANIELS.
